Primary Examiner — Gino Colan(74) *Attorney, Agent, or Firm* — Stetina Brunda Garred
and Brucker(57) **CLAIM**The ornamental design for a gas valve flange, as shown and
described.**DESCRIPTION**FIG. 1 is a front perspective view of the gas valve flange of
the present invention showing my new design;

FIG. 2 is a rear perspective view thereof;

FIG. 3 is a top plan view thereof;

FIG. 4 is a front elevational view thereof;

FIG. 5 is a side view thereof; and,

FIG. 6 is a rear elevational view thereof.

The dotted lines shown in the figures are for the purpose of
illustrating portions of the gas valve flange and form no part
of the claimed design.**1 Claim, 3 Drawing Sheets****FIG. 1**

FIG. 2

FIG. 3**FIG. 4**

FIG. 5

FIG. 6
